A. E. WALKER

CASEMENT WINDOW

Filed Aug. 28, 1924

UNITED STATES PATENT OFFICE.

ARCHIE E. WALKER, OF PORTLAND, OREGON.

CASEMENT WINDOW.

Application filed August 28, 1924. Serial No. 734,772.

To all whom it may concern:

Be it known that I, ARCHIE E. WALKER, a citizen of the United States, and a resident of Portland, county of Multnomah, State of Oregon, have invented a new and useful Casement Window, of which the following is a specification.

This invention relates to casement windows, especially of the in-swinging type of windows and has for its object an improved weather strip construction for preventing wind and rain from passing between the window sill and sash when the sash is closed, and also provides for locking the window in closed position.

In the drawings hereto, Figure 1 is an elevation of the lower part of an in-swinging casement window positioned in its window frame, all as seen from the inside of the room, and with a portion of the sash broken away to reveal the construction of the weather strip.

Figure 2 is an enlarged vertical section of the sash and sill as seen from the line 2—2 of Figure 1.

Figure 3 is a front view of the link connection which lifts the strip when the knob is turned, and Figure 4 shows the locked position of the link with the strip raised.

In further detail, the drawing shows the usual window frame 1 with a casement sash 2 therein and hinged at 3 to swing toward the observer and which in this case is supposed to be inward.

At the lower edge of the sash is a movable strip 4 which is raised or lowered by turning the knob 5, but which is resiliently urged downward by spiral springs 6 seated in depressions 7 surrounding guide pins 8 fixed in the sash but slidably projecting into the strip for guiding its rising and falling movements.

In Figure 2 the relation of the strip 4 to the sill is clearly shown and it will be observed as having a stepped lower edge 4' to overhang the rear stool or raised edge 9' of the sill 9.

The strip also has a tongue 10 along its upper edge sliding in a slot 11 in the lower edge of the sash and is further guided by metal plates 12 and 13 secured to the sash and projecting downwardly on opposite sides of the strip 4 and which plates, espe-

cially the forward one 13, prevent the entrance of moisture to the strip which might otherwise run down the window and gain an entrance to the working parts.

In this connection it should be observed that the plate 13 is bent at right angles to pass under the forward edge of the sash and then again to pass upward inside of the slot 11, and again bent to lie against the upper wall of the slot and to which it is secured, thus forming an absolute barrier against the rains gaining admission through any crevices.

At the center of the tongue 10 of the strip is a hook 14 over which a link 15 is pivoted for raising the strip in the slot upon turning the knob 5.

The knob 5 has a shank 16 rotatably supported in a suitable socket 17 secured to the sash, and at the inner end of the shank is a plate 18 having two projecting pins 19 and 20, one of which (19) engages the link to raise it with a crank-like motion upon turning the shank in the direction indicated by the arrow in Figure 3 of the drawing, while the other pin (20) acts as a stop against a cut out portion 15' of the link at a time when the link has been carried just over center so that the strip will lock in elevated position upon turning the knob as far as it will go to permit free opening or closing of the window.

In contemplating Figure 2, it will be seen that with the strip lowered and interlocked with the stool as shown, the sash is also locked against opening from the outside, thereby dispensing with any other locking device, at least, at the lower end of the sash.

I claim:

In a window having a hinged sash, a movable weather sealing strip at the edge of the sash adapted to engage the frame of the window, and hand controlled means on the sash adapted for withdrawing the strip from such engagement comprising a revolvably supported knob having a shank projecting into the sash above the groove and carrying two pins at its inner end, and a link pivotally connected to one pin and to the strip adapted to stop against the other pin when the strip is withdrawn.

ARCHIE E. WALKER.
